UNITED STATES PATENT OFFICE.

DANIEL B. ROCK, OF FAIRFIELD, PENNSYLVANIA.

DESIGN FOR A FRAME FOR FRUIT-GATHERERS.

SPECIFICATION forming part of Design No. 31,152, dated July 4, 1899.

Application filed May 20, 1899. Serial No. 717,649. Term of patent 14 years.

To all whom it may concern:

Be it known that I, DANIEL B. ROCK, a citizen of the United States, residing at Fairfield, in the county of Adams, State of Pennsylvania, have invented and produced a new and original Design for a Frame for Fruit-Gatherers, of which the following is a specification, reference being had therein to the accompanying drawings.

10 Figure 1 is a perspective of a frame for a fruit-gatherer. Fig. 2 is a side elevation thereof, and Fig. 3 is a plan.

As shown in the drawings, the leading or material feature of my design consists of the 15 curved frame A, having straight portions A', and the connecting corrugated fingers or loops B, arranged across the longer diameter of the frame, with their vertical portions at equal

distances from each other, substantially as shown in the drawings. The frame A is provided at its opposite end from said loop with parallel spaced straight members C. The members C are disposed at a slight angle to the curved frame A, while the fingers B are also at an oblique angle to said frame.

Having described my invention, what I claim as new, and desire to secure by Letters Patent, is—

The design for a frame for fruit-gatherers, substantially as herein shown and described.

30 In testimony whereof I affix my signature in presence of two witnesses.

DANIEL B. ROCK.

Witnesses:

JOSEPH STONENFER,
WM. P. QUIMBY.
